UNITED STATES PATENT OFFICE.

BAYLIES FRANKLIN PHILLIPS, OF TAUNTON, MASSACHUSETTS, ASSIGNOR
TO NOYES & NUTTER MANUFACTURING COMPANY, OF BANGOR, MAINE.

DESIGN FOR A STOVE.

SPECIFICATION forming part of Design No. 35,145, dated October 1, 1901.

Application filed July 13, 1901. Serial No. 68,265. Term of patent 14 years.

To all whom it may concern:

Be it known that I, BAYLIES FRANKLIN PHILLIPS, a citizen of the United States, residing at Taunton, in the county of Bristol and Commonwealth of Massachusetts, have invented and produced a new and original Design for Stoves, of which the following is a specification, reference being had to the accompanying drawing, forming a part thereof.

10 My invention is a new and original design for stoves, and is fully illustrated in the accompanying drawing, which shows my design in perspective.

As illustrated, the stove consists of a base 15 A, having surface ornamentation, the base terminating in legs, while surmounting this base is a rectangular body B, seated upon a flanged section C, which in turn rests upon the base. Surmounting the rectangular body 20 portion is a cap D, which has a flange d overhanging the body portion. The cap is surmounted by a palmette projection 9, having scroll extensions 10. The body has raised

panels bearing ornamentation and also contains imitation corner-posts on each side of 25 the raised central panel. The surface ornamentation consists of a palmette 1, arranged centrally of the sides of the base, surmounted by scrolls 4, corner-scrolls 2, and intermediate scrolls 3. The rectangular body B has 30 vertical panels 5, having scrollwork therein surmounted by rosettes 6, while scrollwork 7 covers the central portion of the sides of the body. The cap D has an intermediate portion in imitation of fretwork. 35

I claim—

The design for a stove as herein shown and described.

In testimony whereof I have signed my name to this specification in the presence of 40 two subscribing witnesses.

BAYLIES FRANKLIN PHILLIPS.
